DESIGN FOR A PORTABLE BARBECUE OR SIMILAR ARTICLE

John Shirley Ward, Pasadena, Calif., assignor to
A. C. Mfg. Co., Van Nuys, Calif., a corporation
of California

Application November 21, 1944, Serial No. 116,467

Term of patent 14 years

(Cl. D81—10)

To all whom it may concern:

Be it known that I, John Shirley Ward, a citizen of the United States residing at Pasadena, in the county of Los Angeles and State of California, have invented a new, original, and ornamental Design for Portable Barbecue or Similar Article, of which the following is a specification, reference being had to the accompanying drawing, forming a part thereof.

The figure is a perspective view of a portable barbecue or similar article, showing my new design.

The side of the portable barbecue opposite that shown in the figure is substantially like the shown side, and the end opposite that shown is substantially plain.

I claim:

The ornamental design for a portable barbecue or similar article, substantially as shown and described.

JOHN SHIRLEY WARD.
